CLAIM

The ornamental design for packaging for bottle, as shown and described.

DESCRIPTION

FIG. 1 is a front view of the packaging for bottle;
FIG. 2 is a right side view of the packaging for bottle;
FIG. 3 is a left side view of the packaging for bottle;
FIG. 4 is a top view of the packaging for bottle;
FIG. 5 is a rear view of the packaging for bottle;
FIG. 6 is a bottom view of the packaging for bottle;
FIG. 7 is a perspective view of the packaging for bottle; and
FIG. 8 is a perspective view of the packaging for bottle.
The broken lines are for the purpose of illustrating
unclaimed portions of the packaging and form no part of the
claimed design.
